ATTORNEY.

UNITED STATES PATENT OFFICE.

THERESE FRANZ, OF BERLIN, GERMANY.

CORSET-CLASP.

SPECIFICATION forming part of Letters Patent No. 224,413, dated February 10, 1880.

Application filed September 20, 1879.

To all whom it may concern:

Be it known that I, THERESE FRANZ, of the city of Berlin, Empire of Germany, have invented certain new and useful Improvements in Corset-Clasps, of which the following is a specification.

Corset-clasps have heretofore been constructed in which one of the plates is formed in a single piece and the other formed of sections, 10 jointed or pivoted to each other, the plates being provided with fastening devices for connecting and holding them together, the object of such construction being intended to permit the corset to be released to relax and 15 ease the person of the wearer without entirely disconnecting the clasps.

As thus made the corset-clasp is very objectionable, owing to one of the plates being practically rigid, or made in a single piece, 20 which has the effect of giving to the wearer a one-sided or deformed appearance when the jointed plate is unfastened, owing to the edge-wise bending of the linked busk, permitting a greater protuberance of the breast and stomach than does the rigid busk, besides rendering 25 the corset extremely uncomfortable.

My invention overcomes these serious objections, and provides corset-clasps which can be conveniently and rapidly unfastened at 30 the stomach of the wearer, and each side permitted to gracefully relax, not affecting the shape of the person, and providing perfect comfort while maintaining the symmetrical and comely appearance of the person, and enabling 35 the wearer to lean forward or assume other positions with perfect ease and comfort.

To this end my invention consists in a corset-clasp each member of which is formed of separate parts pivoted together at their 40 joining ends, that jointed portion which lies over the stomach being, respectively, provided with an eye and a hook, and the other jointed portions being provided with suitable fastening devices, in such manner that the 45 wearer can, by inserting the fingers through the buttoned portion of the dress, raise the hook from the eye, and instantly permit the clasps at that portion which lies over the stomach of the wearer to uniformly separate at 50 each side of the busk, thereby releasing and relieving the stomach and providing perfect comfort, while not detracting from the symmetrical and comely appearance of the figure.

In the accompanying drawings, Figure 1 55 represents a plan view of the corset-clasp con-

nected together, and Fig. 2 a similar view, showing the corset released to permit relaxation of the wearer at the stomach.

Referring to the drawings, it will be seen that each corset-clasp is composed of three 60 sections, A B C and A' B' C', jointed or pivoted together at their adjoining ends, as at E E' F F'.

The lower jointed ends, A A', are provided, respectively, with an eye, D, and button D', 65 which are adapted to engage each other, and the upper ends of the jointed portions C C' are provided with a similar eye and button.

The pivotal portions B B' C C' lie over the stomach, and are provided, respectively, with 70 an eye, H, and a pivoted hook, G, adapted to engage with each other.

As thus constructed, that portion of the clasps which lies over the stomach of the wearer can be rapidly and conveniently released by 75 simply raising the hook G from engagement with the eye H, when the opposite clasps will separate and permit the person of the wearer to relax, and owing to both sides uniformly separating at the stomach of the wearer the 80 graceful and comely appearance of the wearer is not marred, while the corset is rendered perfectly comfortable, enabling the wearer to lean forward or assume other positions with perfect ease.

In fastening or unfastening the hook it is only necessary to insert the fingers through the buttoned portions of the dress and raise or depress the hook, which can be accomplished with such perfect convenience as not 90 to be noticeable.

In order to fasten the hook, I provide the end of the hook with a cord, which, being within convenient reach of the wearer, can be grasped to draw down the hook to engage 95 the eye.

Having fully described my invention, what I claim is—

A corset-clasp each member of which is formed of separate plates pivoted together 100 at their adjacent ends, the intermediate pivoted plates being provided, respectively, with an eye and a pivoted swinging hook adapted to engage and disengage each other, all constructed and arranged substantially as and 105 for the purpose set forth.

THERESE FRANZ.
